[57] CLAIM

The ornamental design for a scanner body front end portion,
as shown and described.

DESCRIPTION

FIG. 1 is an isometric view of a scanner body front end portion;

FIG. 2 is a bottom plan view of a scanner body front end portion;

FIG. 3 is a top plan view of a scanner body front end portion;

FIG. 4 is a front elevational view of a scanner body front end portion;

FIG. 5 is a left side elevational view of a scanner body front end portion; and,

FIG. 6 is a right side elevational view of a scanner body front end portion.

The broken lines are shown in the views for illustrative
purposes only and form no part of the claimed design.
